CLAIM

The ornamental design for a swimming pool water cooler, as shown and described.

DESCRIPTION

FIG. 1 is an oblique perspective of the swimming pool water cooler showing our new design;

FIG. 2 is a view of the front side of the swimming pool water cooler;

FIG. 3 is a view of the back side of the swimming pool water cooler;

FIG. 4 is a view of the left side of the swimming pool water cooler;

FIG. 5 is a view of the right side of the swimming pool water cooler;

FIG. 6 is a view of the bottom left side of the swimming pool water cooler; and,

FIG. 7 is a view of the bottom right side of the swimming pool water cooler.

In the drawings, the broken lines depict unclaimed subject matter only and form no part of the claimed design.
